ABSTRACT

The goods to be irradiated are moved by fluid actuated rams into a rotary lock and then into a chamber where the goods are moved about a radiation source by other fluid actuated rams. The goods are moved from the rotary lock in a forward manner and then displaced therefrom for movement about the radiation source. The goods are returned to the rotary lock in a reverse manner.

**IRRADIATION APPARATUS WITH A ROTARY
LOCK AND WITH CAMS TO MOVE OBJECTS TO
BE IRRADIATED**

This invention relates to an irradiation apparatus. More particularly, this invention relates to an irradiation apparatus for radiating conveyed goods in a continuous manner.

Heretofore, various types of irradiation devices have been known for radiating conveyed goods. For example, devices have been constructed with a rotatable wheel mounted eccentrically in a shielded housing with a specimen holder at one point of the wheel so as to carry a specimen first from the outside of the housing to the inside for radiation and then back to the outside. Generally, these devices have only permitted a single specimen to be subjected to a radiation treatment at any one time. In other instances, various conveyors have been used to move a series of goods about a radiation source. However, these conveyors have usually required rather large and expensive housings and conveyor actuating systems.

Accordingly, it is an object of the invention to provide a simple drive system for moving a series of charges in a continuous manner through an irradiation zone.

It is another object of the invention to provide a portable irradiation apparatus.

It is another object of the invention to irradiate charges in a simple efficient economical manner.

Briefly, the invention provides an irradiation apparatus which is constructed with a shielded irradiation chamber, a rotary lock in a wall of the chamber for receiving charges to be irradiated within a recess, means for conveying the charges in a path around a radiation source mounted within the chamber and means for moving the charges in a straight line between the recess of the rotary lock and the path.

In one embodiment, a device is provided in the region of the rotary lock to move the charges in a direction perpendicularly of the straight line of movement between the recess and path so as to initiate movement about the irradiation source and to return the charges to position in front of the recess.

In another embodiment, a device is provided in the region of the rotary lock to move the charges perpendicularly of the straight line of movement between the recess and path so as to initiate movement about the irradiation source while another device is provided to move the charges out of the path directly into the recess.

In still another embodiment, the means for moving the charges between the recess of the rotary lock and the path about the irradiation source is mounted within the rotary lock and includes a reciprocally mounted tray. The tray is movable from a position within the recess to a position within the path and vice versa so as to deliver or receive a charge.

In all of the above embodiments a transport means is also provided to move the charges into and out of the recess of the rotary lock when the recess is facing away from the irradiation chamber. Further, the transport means serves to move the charges into and out of the recess in the same line as the charges are moved into and out of the irradiation path within the irradiation chamber.

The apparatus requires only a very simple drive for the rotary lock as the lock need only occupy two positions in order to introduce charges into the irradiation chamber. One of these positions will be when the recess faces away from the chamber when an irradiated charge is removed from the recess and replaced by a charge to be irradiated. The rotary lock may then be rotated through 180° until the recess faces the chamber when the charge to be irradiated is placed on the path around the irradiation source and replaced in the recess by an irradiated charge.

As the rotary lock contains only one recess, the lock can be made of smaller diameter than would be necessary if the lock had a number of recesses.

Conveniently, the path of movement about the irradiation source is rectangular and the means for conveying the charges includes a device in the region of the rotary lock and three other devices, each being situated at each corner of the path.

These and other objects and advantages of the invention will become more apparent from the following detailed description and appended claims taken in conjunction with the accompanying drawings in which:

FIG. 1 illustrates a horizontal section through one embodiment of an irradiation apparatus according to the invention;

FIG. 2 illustrates a horizontal section through another embodiment of an irradiation apparatus according to the invention;

FIG. 3 illustrates a horizontal section through a third embodiment of an irradiation apparatus according to the invention; and

FIG. 4 illustrates a view taken on line A-B of FIG. 3.

Referring to FIG. 1, the irradiation apparatus has a block 1 of shielding material, for example, concrete, which encloses an irradiation chamber 2 containing a source of gamma radiation, for example Cobalt 60, which is in the form of a plate 3. The material to be irradiated is moved in the form of charges 4 in two rows, one on each side of the radiation source 3, over a sliding surface which forms the floor of the chamber 2; each charge follows a rectangular path. At each of the four corners of the path is a ram 5a to 5d of a conveying means which is mounted in the block 1 and partly enclosed in lead by means of which the charges 4 are moved around the rectangular path. For reasons of space, the ram 5d is situated below the floor of the chamber 2 and a plate 6 is mounted on its piston rod which projects into the irradiation chamber through a slot 7 in the floor.

40

45

50

55

60

65

A rotary lock 10 is situated in the wall of the shielding block 1 adjacent one of the short sides of the irradiation chamber 2. This lock 10 consists basically of a circular plate having an upstanding annular wall 11, e.g., of lead, mounted thereon. The wall 11 is provided with a gap at one part which extends over the entire height of the wall to form an opening 12 through which a charge 4 can be introduced into or removed from the recess so formed in the lock 10.

In order to move a charge out of the rotary lock 10, a transfer device in the form of a ram 13 is mounted in the recess of the lock 10 and is connected to a suitable actuating means (not shown) which actuates the piston of the ram 13 to move the charges forwardly out of the lock 10. Further, in order to rotate the rotary lock 10

65

between a position in which the recess faces outwardly of the chamber 2 and a position (as shown) in which the recess faces into the chamber 2, which positions are in alignment with each other, i.e., 180° apart, a toothed sector 79 is mounted below the circular plate of the lock 10 and is fixedly connected to the lock 10. The sector 79 meshes with a correspondingly toothed rack 80 which forms an extension of a reciprocal piston rod 81 of a servo-motor 82 so as to be oscillated upon reciprocation of the rack 80 by the servo-motor 82. The rotary lock 10 is thus driven through 180°.

In order to move a charge 4 into the rotary lock 10 from within the chamber 2, a transfer device in the form of a ram 14 is mounted between two rows of charges 4 in the chamber 2 opposite the ram in the rotary lock 10. This ram 14 is actuated by a suitable means (not shown) to return an irradiated charge 4 into the recess of the rotary lock. In addition, a ram transfer device in the form of a 15, situated outside the shielding block 1 and opposite the ram 13, serves to move a charge 4 into the rotary lock 10 from outside the shielding block 1. The rams 13 to 15 are arranged in substantially the same vertical plane.

A transport means is disposed outside the wall of the shielding block 1 for moving the charges 4 to and from the rotary lock 10 when the lock 10 is positioned with the recess facing outwardly of the chamber 2. This transport means includes a supply conveyor 16 to the right of the ram 15 as viewed on which the charges 4 to be irradiated are supplied and a roller conveyor 18 to the opposite side of the ram 15 on which irradiated charges are removed.

It is noted that each of the rams 5a to 5d, 13, 14, 15 and 17 consists of a piston and cylinder and is operated by a pressure fluid, e.g., air, as is known. The feed lines for the pressure fluid and the control mechanism are omitted from the drawings for the sake of clarity.

The apparatus operates as follows: The charges which are to be irradiated move one after the other along the supply conveyor 16 until they are in front of the ram 17, which displaces one charge at a time to the left as seen in FIG. 1. The rotary lock 10 is rotated at the same time to a position 180° from the position shown in FIG. 1, so that the opening 12 faces the ram 15. The charge is then pushed by the ram 15 into the lock 10, which is then rotated by the servo-motor 82 into the position shown. Next, the ram 13 pushes the charge 4 out of the lock 10 into the position indicated by chain-lines in the irradiation chamber 2 in the path of movement about the radiation source 3. The ram 5a then displaces the charge perpendicularly to the right as viewed until the charge is above the groove 7. During the next stage, the ram 5b moves the left-hand row of charges one charge width so as to make room for a charge in front of the ram 5b. The ram 5c then moves a charge from the right-hand row into the left-hand row. The ram 5d then moves the right-hand row of charges one charge width. Thereafter, the ram 5a moves the charge immediately in front of it into the position shown by chain-lines. This charge which has been irradiated is pushed by the ram 14 into the rotary lock 10, which is then rotated by means of the servo-motor 82 so that the opening 12 faces the ram 15. The irradiated charge is then pushed out of the lock 10 by the ram 13, and the ram 17 moves this charge onto the

roller conveyor 18, on which it rolls away, and then brings a new charge in front of the opening 12.

It is noted that the various motions of the respective rams and servo-motor are synchronized in any suitable known manner so as to effectuate the above operation. As such a synchronism is well known, such is not further described.

Referring to FIG. 2, wherein like reference characters refer to like parts as described above, the shielding block 1 is provided with an elongated irradiation chamber 2 which is disposed perpendicularly of the transport means for supplying and removing the charges 4. Further, rams 5a to 5d are provided adjacent the corners of the irradiation chamber 2, and the rotary lock 10' is situated at one corner in such a way that the ram 5d at the adjacent corner also serves to introduce the charges 4 into the lock 10'. This arrangement has the advantage that the ram 14 provided in the embodiment shown in FIG. 1 can be omitted. Also, there is no ram underneath the floor of the chamber 2, and the minimum distance between the two rows of charges is not determined by the width of the ram 14. The rotary lock 10' whose basic construction is the same as that of the rotary lock 10, is smaller in diameter than the latter. In fact, the diameter of the lock 10' is less than the wall thickness of the shielding block 1 at this point. This reduction is possible because the ram 13' inside the lock is different in construction from the ram 13 inside the lock 10. The length of the casing of the ram 13' is shorter than the stroke of its piston, for example, due to a conventional telescopic construction of the piston.

In operation, a charge 4 which is to be irradiated is introduced into the lock 10' and then into the position 35 as shown in the same manner as has been described with reference to FIG. 1. In the next stage, the ram 13' pushes the charge out of the lock 10' to a position in front of the ram 5a. The ram 5b then pushes a charge of the left-hand row which is in front of it in front of the ram 5c on the right-hand side. The ram 5a now pushes the left-hand row forwardly a half or a whole charge width. The irradiated charge pushed into the lock by the ram 5d is then (after the lock 10' has rotated 40 through 180°) transferred onto the roller conveyor 18 by means of the rams 13' and 17 as already described with reference to FIG. 1.

Apart from the advantages mentioned above, the apparatus shown in FIG. 2 has the further advantage that 50 the irradiation chamber 2 is smaller and the weight of the shielding block 1 is therefore reduced.

Referring to FIGS. 3 and 4, the irradiation apparatus has a rotary lock 10'' containing a tray 20 which slides in two grooves 21 having triangular cross-sections. The 55 end of the tray 20 which is on the right in FIG. 4 carries two upwardly projecting lugs 22, each of which has a slot in which a pivot 24 is slidably mounted. Each pivot 24 is mounted on a two-armed lever 25 which is mounted on a pin 26 carried in the annular wall of the rotary lock. The upper ends of the two two-armed levers 25 are connected by a crosspiece 27 which has a knob 28 in the middle. This knob 28 projects into a U-shaped guide 29 which is open at the bottom and at both ends and is attached to the end of a piston rod 30 60 of a ram 31. As the piston of the ram 31 moves to the right in FIG. 4, each lever 25 pivots about the pin 26 to cause the sliding tray 20 to be displaced to the left

along the grooves 21 out of the lock 10" and onto grooves 33, which have triangular crosssections and form extensions of the grooves 21 in the floor of the irradiation chamber 2. This extended position of the sliding tray 20 and the associated positions of the levers 25 are indicated by chain-lines in FIG. 4.

In order to permit the guide 29 to move backwards and forwards, a straight groove 35 which opens downwardly is provided in the shielding block 1. Both ends of this groove 35 lead into an annular groove 36, again open downwardly, which has a rectangular cross-section and is arranged to be concentric with the rotational axis of the rotary lock 10". With the sliding tray 20 in the position shown by solid lines, the lock 10" can be turned while, the knob 28 (projecting sideways from the guide 29) moves in the annular groove 36. This annular groove 36 therefore serves to guide the sliding tray 20 so that no relative motion occurs between the sliding tray 20 and rotary lock 10" when the lock rotates.

Grooves 38 having triangular cross-sections and corresponding to the grooves 33 inside the irradiation chamber 2 are provided on the outside of the shielding block 1 so that the sliding tray 20 can still be extended when the lock 10" has turned through 180°. The lock 10" rests on a ball thrust bearing 39 and is set into the floor of the shielding block 1, to prevent gamma radiation from escaping under the end of the lock. For the same reason, a shoulder 40 is provided at the upper end 30 of the rotary lock which projects into the shielding block.

The apparatus shown in FIGS. 3 and 4 operates as follows. In order to introduce a charge for irradiation, the rotary lock 10" is brought out of the position shown into a position rotated through 180°. At the same time, the piston of the ram 31 is moved to the right, the latter beginning movement somewhat later than and ending somewhat earlier than the rotary lock 10". As a result, the knob 28 can leave the guide 29 at the point shown and then re-enter the guide 29 when the guide 29 has moved to its right-hand position. It is therefore unnecessary for the ram 31 to be constructed so as to have an intermediate position between its two end positions. The piston of the ram 31 is then moved to the left, and the sliding tray 20 comes out of the lock 10" along the grooves 38. A charge for irradiation is pushed by the ram 17 onto the sliding tray 20, which is then withdrawn into the lock 10" by means of the ram 31. Next, the lock is turned through 180°, the piston of the ram 31 again starting later and arriving earlier in its left-hand position, so that the position shown by solid lines in FIG. 4 is reached. By means of the ram 31, whose piston moves to the right, the tray 20 runs onto the grooves 33, whereupon the ram 5a displaces the charge to be irradiated to the right as viewed in FIG. 3 so that it joins the right-hand row of charges. The ram 5b then moves the left-hand row forward one charge width to bring an irradiated charge onto the tray 20. While the ram 5c and then the ram 5d are fulfilling their functions, the ram 31 withdraws the tray 20 into the rotary lock 10", so that the position shown by solid lines is reached again. Next, the lock 10" turns through 180°, while the piston of the ram 31 moves to the right. When this piston next moves to the left, the tray 20 is moved along the grooves 38 and the ram 17 is operated

to move the irradiated charge onto the roller conveyor 18, on which it rolls away, while at the same time a new charge is pushed onto the tray 20 in order to be irradiated.

In the apparatus shown in FIG. 3 and 4, there is a further reduction in the diameter of the rotary lock and in the number of rams, the rams 13 and 13' being omitted. The movement of the sliding tray 20 by means of the ram 31, like movement of the lock by means of the servo-motor 82, has the advantage that, because the piston occupies limit positions, the sliding tray is always certain to reach its withdrawn and extended positions.

The apparatus have been described as being of permanent construction; however, the apparatus can also be constructed in a portable or movable manner. In such a case, the shielding block might be of lead instead of concrete. Also, the shielding block might be built of separate, prefabricated elements light enough to be transported. By this means, an apparatus can be built which could be disassembled when required and re-erected on another site. It is also possible for each charge 4 to be composed of several smaller charges.

What is claimed is:

1. An irradiation apparatus comprising a wall defining a shielded irradiation chamber for housing a radiation source therein at a radiation source station; means for conveying charges to be irradiated in a path around said radiation source station within said chamber, said path including at least two straight line segments; a rotary lock in said shield wall having a recess for receiving charges to be irradiated, said rotary lock having a single position in which said recess faces outwardly of said chamber to receive and unload a charge and a single position in which said recess faces inwardly of said chamber, to receive and unload a charge; means for loading and unloading to and from said recess, said means including at least two transfer devices situated in substantially the same plane for moving the charges in a straight line; and a device in the region of said rotary lock for moving charges within said chamber in a direction perpendicular to said straight line between said straight line and said path around said radiation source station.

2. An irradiation apparatus as set forth in claim 1 in which said path is rectangular and said means for conveying the charges includes said device and three other devices, each device being situated at a respective corner of said path.

3. An irradiation apparatus as set forth in claim 2 in which said rotary lock is situated at one corner of said path so that said device at an adjacent corner is arranged to load said rotary lock when said recess faces said irradiation chamber.

4. An irradiation apparatus as set forth in claim 1 further including a charge-receiving member connected to one of said transfer devices to be moved radially into and out of said rotary lock.

5. An irradiation apparatus as set forth in claim 4 wherein said one transfer device includes a piston rod movable in a fixed cylinder, said piston rod being ar-

ranged to be coupled to said member when said member is moved out of said rotary lock and to be disconnected from said member when said member is in said rotary lock and said rotary lock rotates.

6. An irradiation apparatus as set forth in claim 1 further including a fluid-actuated ram connected to a rack, and a toothed element attached to and between said rack and said rotary lock for rotating the rotary

lock upon reciprocation of said rack.

7. Apparatus as set forth in claim 1 in which said means for moving the charges in a straight line comprise fluid-actuated rams.

5 8. Apparatus as set forth in claim 1 in which said device in the region of said rotary lock is a fluid-actuated ram.

UNITED STATES PATENT OFFICE
CERTIFICATE OF CORRECTION

Patent No. 3,686,502

Dated August 22, 1972

Inventor(s) Adolf Sieber

It is certified that error appears in the above-identified patent and that said Letters Patent are hereby corrected as shown below:

Column 2, line 45, "ran" should be --ram--

Column 3, lines 19 and 20, "ram transfer device in the form of a 15" should be --transfer device in the form of a ram 15--.

Signed and sealed this 9th day of January 1973.
